REINFORCED CONCRETE CONSTRUCTION MEMBER.

APPLICATION FILED JULY 8, 1907.

2 SHEETS—SHEET 2.

UNITED STATES PATENT OFFICE.

ROBERT ANDERSON, OF CINCINNATI, OHIO, ASSIGNOR TO THE FERRO-CONCRETE CONSTRUCTION COMPANY, OF CINCINNATI, OHIO, A CORPORATION OF OHIO.

REINFORCED-CONCRETE-CONSTRUCTION MEMBER.

No. 894,997.

Specification of Letters Patent.

Patented Aug. 4, 1908.

Application filed July 8, 1907. Serial No. 382,666.

To all whom it may concern:

Be it known that I, ROBERT ANDERSON, a citizen of the United States of America, and resident of Cincinnati, county of Hamilton,

5 State of Ohio, have invented certain new and useful Improvements in Reinforced-Concrete-Construction Members, of which the following is a specification.

My invention relates to the horizontal 10 members of reinforced concrete construction such as beams, girders, floors and walls. Its object is a means of reinforcing such construction members, in which no breaks occur in the reinforcement at points where there is 15 tension, and in which the reinforcement is distributed to the parts of the construction member in proportion to the tension to which such parts are subject in use and in which the reinforcing bars may be manufactured and 20 set in place in the construction very readily. This object is attained by the means described in the specification and illustrated in the accompanying drawings, in which.

Figure 1 is a view in side elevation of the 25 reinforcing bars in the position they occupy in the construction member, the dotted line indicating the outlines of the concrete of the construction bar, and of the supports, the straps being omitted in this view. Fig. 2 is a 30 view similar to Fig. 1 but showing the tension bars surrounded with concrete and the straps in place, the concrete being shown in section. Fig. 3 is a sectional view upon an enlarged scale taken upon line $y-y$ of Fig. 2. Fig. 4 35 is a sectional view taken upon line $z-z$ of Fig. 2. Fig. 5 is a sectional view similar to Fig. 4 but showing four bars in place of two bars. Fig. 6 is a detail elevation upon an enlarged scale of the reinforcing bar shown in 40 Figs. 1-5. Fig. 7 is a view similar to Fig. 1 but of a modified form of construction. Fig. 8 is a plan view of the tension or reinforcing bar shown in Fig. 7. Figs. 9, 10, 11 and 12 45 are sectional views upon an enlarged scale taken upon lines $x-x$, $w-w$, $v-v$, and $r-r$ of Fig. 7. Fig. 13 is a detail elevation upon an enlarged scale of the reinforcing bar shown in Figs. 7-12.

In the accompanying drawings I have 50 illustrated my invention as applied to a reinforced concrete beam.

In Fig. 1 the beam, A, is upheld by supports, B, B', B², B³, and B⁴.

The tension elements consist of steel bars, 55 which have an arch, C, and straight ends,

c, c'. The end, c, extends over the center of a support, B, in the lower part of the beam, A, to a point beyond the central point between the support, B, and its adjacent support, B'; thence the arch, C, extends at an 60 angle to a point, c', to the left of the support, B'. Thence the bar lies in a horizontal plane in the upper part of the beam, to a point, c², upon the opposite side of the support, B'. Thence the bar extends at the same angle to the horizontal as the opposite side of the arch to the straight part, c, and thence continues in the lower part of the beam to a point near the center of the third support, B². The second steel bar starts 70 near the center of the second support, B', lies adjacent to the first bar, its arch extends over the second support, B² and its ends, c', extend to a point above the third support, B³, in the manner described for the 75 first bar. At the ends of the beam, viz., at the side walls of the building, there are short steel bars, C', whose semi-arches terminate in hooked ends, c⁴, above the supports, B⁴, and whose straight ends, c⁵, extend in the 80 lower part of the beam and terminate in the center of the supports, B', B³, respectively. At points in the beam midway between the supports the usual straps, D, extend upwardly and have their ends, d, d', bent over 85 into the concrete of the floor, E. At the sides of the supports there are similar straps, D'. In this construction it is seen that the greatest amounts of metal in the beam occur at the points where the tension 90 is greatest, viz., in the lower parts of the beam midway between the supports; that above the supports in the upper part of the beam the reinforcing bars are integral and are located in a position such as to resist the 95 reverse moment occurring above the supports; that the laps or breaks between a bar and its adjacent bar occur above a support in the lower part of the beam, where the bending moment is nil. Thus no breaks 100 occur in the reinforcing bars where there is a bending or tension force in the beam.

It would have been an obvious expedient to make the part, c', of the first bar, C, on the left of Fig. 1 integral with the part, c, of the third bar, C, and to have made the part, c, of the second bar integral with the part, c⁵, of the bar, C' upon the right. This is a modification that might be used in floor slabs:

Referring to Figs. 7—13, the supports, B^s , B^s , B^s , B^s and B^s are similar to the supports, B — B^s . The arch C^s in a steel bar occurs to one side of the center, and the straight end, c^s , is shorter than the straight end, c^s . In placing the bars in position they are alternately reversed, that is, two bars are placed side by side, but one being in reverse direction to the other. Thus, the long end, c^s , of one occurs adjacent to the short end, c^s , of the other, and the arch, c^s , of one extends beyond the end of the arch of the other as seen in Fig. 7. The arches of the two bars stand alongside each other, but at 15 a point midway between the supports, the parts, c^s , stand over the parts, c^s , as shown in Fig. 10, while at the ends they diverge as shown in Fig. 11. These pairs of bars are arranged as the single bars are shown arranged in Fig. 1, viz., the first pair starts in the lower part of the beam over support, B^s , their arches stand over B^s , and their ends extend over support, B^s , while the second pair start over support, B^s , their arches stand over support, B^s , and they end over support, B^s . The result is that directly above the support, B^s , where the reverse moment is the greatest, there will be the greater amount of metal and that to the left and to the right of the part of the beam occurring above the support, there will be a decreasing amount of metal in proportion to the decrease in the tension moment.

At the ends of the beams shown in Fig. 7 and Fig. 8 there are two short bars with the semi-arches, C^s , arranged similarly to the short bars at the ends of the beams shown in Fig. 1.

In the modifications shown in Figs. 1—13 it is seen that the laps or breaks occur always in the lower part of the beam above the support where there is no tensional stress; that the metal is distributed in the different parts of the beam in proportion 40 to the amount of tension in those parts; that in these modifications but one form of bar is necessary to be manufactured and that the process of setting the parts in position is a simple one.

50 In the modification shown in Fig. 5 the series of bars are placed side by side similarly to that shown in Figs. 7 and 8 with the exception that the arches, C^s , occur in the center of the bars instead of to one side thereof.

What I claim is:

1. A reinforced concrete construction member for extending over a series of supports consisting of concrete in which are 55 embedded series of bars, each of the bars

of which are arched so as to extend over a support in the upper part of the concrete and having upon each side of an arch straight members to extend over the two adjacent supports in the lower part of the concrete of the member, the bars being arranged so that the arches in one series pass over every other support and the arches in the adjacent series pass over those supports over which the arches in the first do not pass.

2. A reinforced concrete construction member for extending over a second support to a third support and having reinforcing bars, each bar being bent into an arch intermediate its straight ends, said arch extending over the second support in the upper part of the construction member and the ends of the bar being located in the lower part of the construction member and ending 80 above the first and third supports respectively.

3. A reinforced concrete construction member for extending from one support over a second support to a third support 85 and having a series of reinforcing bars, each bar being bent into an arch and having straight ends, said arches extending over the second support in the upper part of the construction member and the ends of the bars being located in the lower part of the member and extending to the first and third supports respectively, the arch in one bar extending more beyond the right of the center of the second support than upon the 90 left thereof and the arch in an adjacent bar extending more to the left of the center of said second support than upon the right thereof.

4. A reinforced concrete construction member for extending over a series of supports having a series of bars made similar in shape, each bar having an arch and straight ends, one of said ends being longer than the other, the bars being placed side by side in the construction member with the arches occurring over the supports and the bars being placed side by side in alternately reversed directions so that the arch occurs more to the left of the center of the support in one bar and more to the right of the center of the support in the next bar and the ends of the bars terminate above the supports in the lower parts of the construction member.
